UNITED STATES PATENT OFFICE

THOMAS RAYMOND CARLEY, OF LOS ANGELES, CALIFORNIA

DESIGN FOR A LADY'S FASHION CANE

Application filed December 20, 1930. Serial No. 38,051. Term of patent 7 years.

To all whom it may concern:

Be it known that I, THOMAS RAYMOND CARLEY, a citizen of the United States of America, residing at Los Angeles, in the county of Los Angeles and State of California, have invented a new, original, and ornamental Design for a Lady's Fashion Cane, reference being had to the accompanying drawing, forming a part thereof.

The figure is a perspective view showing my new design. The reverse side of the cane is substantially the same as the one shown.

I claim:—

The ornamental design for a lady's fashion cane as shown and described.

THOMAS R. CARLEY.
